[57] **CLAIM**

The ornamental design for a fluorescent and reflecting safety vest for pets, as shown and described.

DESCRIPTION

FIG. 1 is a perspective view of a safety vest for pets showing my new design in use;

FIG. 2 is a top plan view of the vest in a flat position;

FIG. 3 is a bottom plan view of FIG. 2;

FIG. 4 is a left side elevational view of FIG. 1, the right side being a mirror image of the left side shown; and

FIG. 5 is a front elevational view of FIG. 1.

The broken line representation of a dog in FIG. 1 is for purposes of illustration only.

FIG. 1

FIG. 2

FIG. 3

FIG. 4

FIG. 5
